STOP MOTION FOR YARN HANDLING MACHINES

Albert E. Winslow, Norwich, Conn., assignor to
Atwood Machine Company, a corporation of
Connecticut

Application November 3, 1943, Serial No. 508,817

5 Claims. (Cl. 57—80)

This invention relates to a yarn handling machine, more particularly to a ring twister and to the stop motion which is associated with the same.

In this twister there is used a supply package having a plurality of parallel wound yarns, one of these is lead to one spindle and another to another spindle. If either of the yarns from the common supply package should break the other yarn or yarns may be drawn from the supply package causing the package to rotate with a consequent waste of length of both the broken and unbroken yarns until the break has been remedied.

One of the objects of this invention is to operate from each of the individual yarns which come from the supply package a control for the supply package so that should either one of these ends break the supply package will be stopped.

Another object of this invention is to connect the stop motion for the separate and individual yarns after separated from the supply package so that they will operate in unison or may be reset in unison.

A more specific object of the invention is to provide a drive and brake arrangement for the supply package operable together for controlling the supply package.

Another object of the invention is to stop the delivery package spindle with the stopping of the supply package.

Another object of the invention is to provide a stop motion which will be extremely simple in construction and positive in its operation.

With these and other objects in view, the invention consists of certain novel features of construction, as will be more fully described and particularly pointed out in the appended claims.

In the accompanying drawings:

Fig. 1 is a face view showing in elevation a fragmental portion of a twisting frame illustrating the supply package, the spindle, and the stop motion mechanism for the supply package;

Fig. 2 is a sectional view through a fragmental portion of a twisting frame looking at right angles to the showing of Fig. 1 and showing substantially the same parts as shown in Fig. 1;

Fig. 3 is a view similar to Fig. 1 showing in section the pulley on the drive shaft which operates the supply package and the movable parts of the stop motion;

Fig. 4 illustrates the operating rod for resetting the stop motion and the foot pedal for operating the same;

Fig. 5 is a sectional view of the frame illustrat-

ing the spindle mounting and drive therefore as well as the supply package and its arrangement with respect to drive;

Fig. 6 is a view taken on substantially line 6—6 of Fig. 5;

Fig. 7 is a section on line 7—7 of Fig. 8;

Fig. 8 is a sectional view through the mounting of the spindle.

This twisting frame has a plurality of mandrels extending axially towards the operator when in front of the machine upon which supply packages are mounted. Each of these mandrels is rotated by means of a pulley from a belt which extends the length of the machine and has one of its surfaces engaging each of these pulleys to drive the same. My stop mechanism is so arranged that the belt is withdrawn from the particular drive pulley which drives the supply package having the broken end and at the same time the belt is withdrawn a brake is applied to the drive pulley to stop the operation of the same and simultaneously the take up spindle is withdrawn from operation and stopped. Trigger means engaged by each of the individual yarns serve to control the brake and idler pulley which control the belt which drives the mandrel upon which the supply package is mounted and also the spindle drive.

With reference to the drawings 10 designates a stand intermediate the ends of the frame which provides a support for the horizontal angle beam 11 from which the guide bracket 12 extends (see Fig. 2) providing a bearing 13 for the reciprocating guide board rods 14 for moving the guide board 15 and guide 16 relative to the spindle 9 and the take up or delivery package 17 thereon. At the upper end of the frame standard there is the horizontal framework 18 supported by the stand 10 and comprising an angle bar 19 and top board 20. This framework is of course duplicated on the other side of the machine which supports similar mechanism in back to back relation, but one-half being illustrated in Fig. 2 or 5.

45 A bearing 21 is fixed to the framework 18 within the angle iron 19 and rotatably supports the shaft 22 upon which the supply package 23 is fixed by suitable mounting mechanism. The yarn 24, 24' delivers from this supply package, which is wound with a plurality of strands in parallel relation, one end 24 to the spindle 17 and the other end 24' to the spindle 17'.

The several shafts 22 have mounted upon them drive drums 25 to engage the back 26 of the V-belt 27 which extends lengthwise of the frame,

the return of the V-belt 27 is shown in 27', Fig. 2.

In order to move the V-belt 27 against a drum 25 an arm 28 (see Fig. 3) extends downwardly from the bearing 21 and supports the bracket 29 which is pivotally mounted on a pin 30 in this arm 28 so that the bracket may rock about the pin 30 as a center. A pulley 31 grooved as at 32 (see Fig. 2) to fit the converging edges of the belt 27 is rotatably carried by the bracket on axle 33 so that as the bracket is pivoted counterclockwise as viewed in Fig. 3 about the shaft 30 it will lift the belt 27 into engagement with the drive pulley 25. This bracket 29 also carries an idler pulley 34 rotatably supported on the axle 35 on the bracket so that as the bracket is rocked clockwise in the opposite direction this pulley 34 will engage the belt and move it clear from the drive pulley 25. At the same time that such movement of the bracket 29 occurs the arm 36 of this bracket which pivotally supports the brake shoe 37 as at 38 will apply this brake shoe to the drive drum 25 to retard its rotation.

An arm 39 on the bracket is secured to a collar 40 which is slidable upon the rod 41. This collar is located between compression spring 42 engaging abutment 43 at one end of the rod and compression spring 44 engaging collar 45 secured to the rod 41. When the bracket is in a position such that the belt 27 drives pulley 25 and the supply package, the rod 41 will be so raised that spring 44 will urge the bracket 29 counterclockwise to release the brake and cause the V-pulley to push the belt against the driving drum 25 as shown in Fig. 1. In this position the spring 42 will be substantially extended and will exert but little pressure upon the collar 40.

A rock lever 46 is pivoted to the bracket on pin 47, its arm 48 carries a member 49 extending into a position above a disk 50 (see Fig. 1) which is driven by the shaft 22 and provided with notches or recesses 51. This member 49 has a laterally extending portion which will drop into one of the notches 51 if permitted to do so, the movement toward the notches being assisted by a tension spring 52 extending from the end of the arm 46 at the lower portion thereof. A feeler arm 53 extends downwardly from the member 49 and has a laterally extending portion 54 against which the yarn 24 engages so as to hold the pivoted lever and the mechanism carried thereby in the position shown in Fig. 1. However, should the yarn 24 break then the portion 54 against which it engages is permitted to swing and the lever 46, 48, with its member 49 will move so that the portion of the member 49 drops into the notches which are rotating, which rotating member through this mechanism forces the bracket 29 downwardly or clockwise about its pivot 30 so as to cause the pulley 34 to move the belt 27 away from the drum 25 and at the same time apply the brake 37.

The rod 41 is provided with a foot pedal 55 pivoted at 56 and connected to the rod as at 57 so that if the rod is in lowered position stepping on the foot pedal 55 will raise the rod so as to reset it and the mechanism which it controls in driving position for the supply package.

The operating mechanism just described is duplicated above the spindle 17' while the yarn 24' is led over a fixed guide 60 and back of the feeler arm 53', 54' which corresponds to the feeler 53, 54 just described. The swinging levers 46, 46' are connected together by a bar 62 while racks 63 and 63' are provided on the two rods 41, 41' connected together by segmental gears

64, 64' and a connecting link 65 which extends between them, weighting means 66, 66' are provided on the ends of the lever arm 67, 67' for balancing the weight for more efficient operation.

5 If either foot pedal at the end of rods 41, 41' is pushed both mechanisms will be reset.

As the rod 41 moves downwardly, other mechanism is also actuated to withdraw the spindle 9 from driving position. The spindle is suitably 10 rotatably supported on the shelf portion 74 (see Fig. 8) of the bracket 70 and is swingingly mounted upon a vertical pivot 71 on the fixed support 72. The spring 73 serves to swing the bracket about the pin 71 as a pivot to cause the whirl 76 to engage and be driven by a belt 77 (see Figs. 5 and 6).

The bracket 70 (see Fig. 7) is so shaped as to provide a shoulder abutment 78 with which a block 79 mounted on the rod 80 may engage to 20 swing the bracket about its pivot 71 to withdraw the whirl 76 from engagement with the belt 77. The rod 80 is actuated by levers 81 pivoted as at 82 and the connected through one arm 83 to the rod 41 while another arm 84 is connected to the 25 rod 80. It will be evident that when the rod 41 is moved to its lower position the bell crank lever 81 will so rock as to cause the rod 80 to move to the right as shown in Fig. 5 or 7 so that the blocks 79 will engage the shoulder 78 and swing 30 the bracket 70 to move the whirl 76 away from the belt 77.

As the whirl moves away from the belt 77 it moves into engagement with a brake 85 (see Fig. 6) which is suitably supported by an arm 86 extending outwardly from some fixed part of the machine as shown at 87 in Fig. 1 so that the spindle will be quickly brought to rest by a braking action upon severing of the yarn.

The spring 73 may be adjusted as to tension 40 by the ratchet 88 and pin 89 which is also carried by the arm 86.

The arrangement of the manipulating arms is such that the whirl 76 will engage belt 77 just prior to engagement of the belt 27 with the drum 45 25 so that the package 17 will be rotating and maintain some pull on the yarn as the drive of the supply package 23 commences.

I claim:

1. In a yarn handling machine, a supply package, a drive drum rotatable therewith and through which the same is driven, a plurality of spindles to which the supply yarn is guided for packaging, a belt adjacent said driving drum, a swinging bracket carrying pulleys on either side 55 of said belt, means to hold said bracket in a position to cause one of said pulleys to maintain the belt in engagement with said pulley to drive the same, means responsive to the breaking of the yarn to move said bracket and cause engagement of the other pulley with the belt to move it from engagement with said drum and a brake carried by said bracket for engaging said drum upon movement of the belt therefrom.

2. In a yarn handling machine, a plurality of 65 supply packages, a driving drum rotatable with each package and through which each package is driven, a common belt for extending along the machine for engaging each drum for rotation thereof, a plurality of spindles to which the yarn supply is guided for packaging the same, feeler arms one for engaging each yarn end directed to said spindles to maintain each feeler in certain position, a pivotally mounted bracket with pulleys on either side of the belt movable in response to the breaking of a yarn end and move-

ment of one of the pulleys into engagement with the belt to withdraw the belt from contact with the driving drum which supplies said broken yarn while leaving undisturbed the other driving drums.

3. In a yarn handling machine, a plurality of supply packages, a driving drum rotatable with each package and through which each package is driven, a common belt for extending along the machine for engaging each drum for rotation thereof, a plurality of spindles to which the yarn supply is guided for packaging the same, feeler arms one for engaging each yarn end directed to said spindles to maintain each feeler in certain position, a pivotally mounted bracket with pulleys on either side of said belt movable in response to the breaking of a yarn end and movement of one of the pulleys into engagement with the belt to withdraw the belt from contact with the driving drum which supplies said broken yarn and at the same time applying a brake thereto while leaving undisturbed the other driving drums.

4. In a yarn handling machine, a supply package, a drive drum rotatable therewith and through which the same is driven, a notched disk also rotatable therewith, a belt for driving said drum, a delivery package to which the yarn from

the supply package is lead, a feeler arm having a portion adjacent said notched disk and a portion for engaging the yarn as supplied to hold the same disengaged from said disk, means carrying said feeler arm and actuated by the disk engaging the arm to stop the motion of said drum and supply package driven thereby.

5. In a yarn handling machine, a supply package having a plurality of yarn ends thereon, a drive drum rotatable therewith and through which the same is driven, a plurality of spindles to which the supply yarn is guided from said supply package for packaging, a belt adjacent said driving drum, a swinging bracket carrying pulleys on either side of said belt, feelers one for engaging each yarn end to maintain each feeler in certain position, means operatively connected to each feeler to hold said bracket in a position to cause one of said pulleys to maintain the belt in engagement with said pulley to drive the same, said feelers being responsive to the breaking of the yarn to engage other means and be moved thereby to withdraw said holding means to permit said bracket to be moved and cause engagement of the other pulley with the belt to move it from engagement with said drum.

ALBERT E. WINSLOW.
